(57) **CLAIM**

The ornamental design for an electronic device, as shown and described.

DESCRIPTION

FIG. 1 is a first perspective view of a first embodiment of an electronic device, taken from above.

FIG. 2 is a second perspective view of the first embodiment of the electronic device, taken from below.

FIG. 3 is a back view of the first embodiment of the electronic device of FIG. 1.

FIG. 4 is a front view of the first embodiment of the electronic device of FIG. 1.

FIG. 5 is a left-side view of the first embodiment of the electronic device of FIG. 1.

FIG. 6 is a right-side view of the first embodiment of the electronic device of FIG. 1.

FIG. 7 is a top view of the first embodiment of the electronic device of FIG. 1.

FIG. 8 is a bottom view of the first embodiment of the electronic device of FIG. 1.

FIG. 9 is a first perspective view of a second embodiment of an electronic device, taken from above.

FIG. 10 is a second perspective view of the second embodiment of the electronic device, taken from below.

FIG. 11 is a back view of the second embodiment of the electronic device of FIG. 9.

FIG. 12 is a front view of the second embodiment of the electronic device of FIG. 9.

FIG. 13 is a left-side view of the second embodiment of the electronic device of FIG. 9.

FIG. 14 is a right-side view of the second embodiment of the electronic device of FIG. 9.

FIG. 15 is a top view of the second embodiment of the electronic device of FIG. 9; and,

FIG. 16 is a bottom view of the second embodiment of the electronic device of FIG. 9.

The broken lines depict portions of the electronic device which form no part of the claimed design.

1 Claim, 16 Drawing Sheets
